[57] CLAIM

The ornamental design for a rim lock, as shown and described.

DESCRIPTION

FIG. 1 is a perspective view of a rim lock showing our new design;

FIG. 2 is a left end elevational view thereof;

FIG. 3 is a top plan view thereof;

FIG. 4 is a right end elevational view thereof;

FIG. 5 is a front elevational view thereof;

FIG. 6 is a rear elevational view thereof;

FIG. 7 is a bottom plan view thereof;

FIG. 8 is a perspective view of a rim lock showing a second embodiment of our new design;

FIG. 9 is a left end elevational view of FIG. 8;

FIG. 10 is a top plan view of FIG. 8;

FIG. 11 is a right end elevational view of FIG. 8;

FIG. 12 is a front elevational view of FIG. 8;

FIG. 13 is a rear elevational view of FIG. 8;

FIG. 14 is a bottom plan view of FIG. 8; and

FIG. 15 is a perspective view of a rim lock showing a third embodiment of our new design, wherein the only difference between the third embodiment and the second embodiment resides in the addition of a latch-retracting pin.
